WINDSHIELD BLADE CLEANING DEVICE

Stan Klein, % Revark Company, Inc., 87-27, 78th St.,
New York, N.Y. 11421

Filed Oct. 16, 1975, Ser. No. 622,829

Term of patent 14 years

Int. Cl. D7—05

U.S. Cl. D7—161

FIG. 1

FIG. 2

FIG. 3

FIG. 4

FIG. 5

FIG. 6

FIG. 1 is a top plan view of a windshield blade cleaning device showing my new design;

FIG. 2 is a side elevational view thereof;

FIG. 3 is an end elevational view thereof;

FIG. 4 is a bottom plan view thereof;

FIG. 5 is a side elevational view showing a second embodiment thereof; and

FIG. 6 is an end elevational view of the second embodiment.

I claim:

The ornamental design for a windshield blade cleaning device, substantially as shown and described.
